APPOINTMENT CLOCK

John K. Lawler and Charles W. Heath, Sioux
City, Iowa

Application August 31, 1931, Serial No. 560,292

6 Claims. (Cl. 161—1)

This invention relates to a clock in which an automatic daily reminder is used and which reminder will be actuated by the clock itself.

- A major purpose of our invention is to provide 5 a means wherein a reminder in the form of appointments to be kept by professional men or others is incorporated, together with a clock, and will serve to keep dates in order and also specific appointments to be kept on these dates.
- 10 Another purpose of our invention is to provide the aforementioned means and with additional means to enable anyone to set the mechanism so that future dates can be notated and then the mechanism set back to the present date.

- 15 A further purpose of our invention consists in placing together with the appointment register, a space for displaying printed matter relative to a variety of goods or merchandise.

- Another purpose of our invention is to provide 20 such a mechanism that will be absolutely accurate and will automatically release the register in a short interval of time daily.

- A still further purpose of our invention is to 25 arrange the parts in a simple manner so they can be driven either from an electric or mechanical clock.

- Another purpose is to provide such an appointment clock so that entries can be made very conveniently and at a suitable angle.

- 30 A further purpose is to provide such a construction which is simple, durable, and inexpensive.

With these and other objects in view, our invention consists in the construction, arrangement and combination of the various parts of our device whereby the objects contemplated are attained, as hereinafter more fully set forth, pointed out in our claims, and illustrated in the accompanying drawings, in which:

- Figure 1 is a front view of the appointment 40 clock, looking directly at the face of the clock and the register,

- Figure 2 is a section taken medially of Figure 1, the section being faked slightly to show the trip mechanism, as hereinafter explained,

- 45 Figure 3 is an enlarged front view of the trip mechanism,

Figure 4 shows the trip mechanism in both of its positions in larger detail,

- Figure 5 is an enlarged view of a portion of the 50 appointment register,

Figure 6 is a section taken along the line 6—6 of Figure 2,

Figure 7 is a section taken along the line 7—7 of Figure 2,

- 55 Figure 8 is a side view of the clock and ap-

pointment register showing where it is used in combination with an electric clock, and

Figure 9 is a detailed section taken on the line 9—9 of Figure 2.

The reference character 10 is used to indicate 60 the clock generally. In order to simplify the description, we will be more specific to the invention as applied to an ordinary spring-wound clock.

The register opening is shown at 11 and is a 65 cut out portion in the slanting portion 12 of the clock 10. Under this cut away portion is placed the base 13 over which the paper 14 travels when it is being unrolled from the feed roll 15. The driven power roll is shown as 16. Small slots 17 70 are spaced equally along the paper roll at the daily intervals on the register.

Now that the majority of the main features of our invention have been shown, it will be best to explain the operation of the device. In the case 75 of the mechanical clock, driven by a spring motor, the mechanism is to be driven from the alarm mechanism 18 which is daily wound by means of the usual key 19. A small pulley cord 20 travels about a suitable pulley 21a attached rigidly to the spring mechanism 18. This cord 20 also travels about the pulley 21.

An additional fibre disc 22 is placed in frictional engagement with the pulley 21 as shown in Figure 9, and this same disc 22 is rigidly secured to the 85 power roll 16 by means of screws 23 which screws also pass through the flanges 24 of the power roll 16.

In a similar manner, the feed roll 15 is attached to its flanges 52 by means of screws 53 and the 90 spacer 54 is also provided.

A thumb screw 25 passes through the side walls 27 of the clock housing and through the spacer 26 and is rigidly secured to the power roll 16.

The trip mechanism consists of the tripping 95 arm 28, the shaft 29, the pins 30 and the trip pin 31.

When the slot 17 is at the position shown in Figure 2, at the same time another slot 17 receives the pins 30. It will be understood that the 100 spacing of these slots 17 is made so that they will appear in the aforementioned positions simultaneously. This spacing is more satisfactorily achieved by means of the idler pulleys 32, 33, 34, and the guide 35.

As long as the pin 31 is away from the trip arm 28, the pins 30 will always be engaged with the slots 17. However, when the pin 31 which is fastened securely to the pulley 21, strikes against the upwardly projecting and slanting portion 36 110

of the trip arm 28, it will be seen that the trip arm 28 will be pivoted about the shaft 29 and the pins 30 will come out of engagement with the slots 17. As soon as this action takes place the pulley

5 21 will tend to turn the power roll 16 and the paper 14 will be wound up on the roll 16 on account of the frictional engagement between the pulley 21 and the fibre disc 22. This action will take place until another pair of slots 17

10 engage with the pins 30, when the pins 30 will drop down into the slots and in case the spring mechanism continues to run, the strength of the paper itself will prevent the roll 16 from further rotation and the friction disc and the pulley

15 21 will still revolve, however without rotating the power roll 16 since the pulley 21 will slide freely along the friction disc 22.

A spring 37 is pinned to the trip arm 28 as shown and this spring provides the proper function for raising or lowering the trip arm 28 under spring action.

When the pins 30 are not engaged with the slots 17, they will merely travel along the paper strip 14 and are made slightly blunt at their ends 25 so as not to tear into the paper.

An extra idler pulley 38 is provided to allow more convenient take-up of the paper roll on the power roll 16.

It will be seen from our construction that the 30 movement of the daily register will be strictly uniform and in no way can it get out of place, since by means of frictional devices as shown in combination with the slots and tripping mechanism, this register will move uniformly between 35 slots for a brief interval of time between days.

The pulley ratio between the pulleys 21a and 21 are such that a complete winding of the alarm mechanism of the clock or other intermittent power device will not cause a complete revolution 40 of the pulley 21, otherwise the tripping device would function more than once daily. Furthermore, the tension in the spring 37 is such that even though the pulley 21 would revolve slightly more than once, this tension would tend 45 to prevent the pin 31 from passing beyond the slanting portion of the fulcrumed arm since the power of the alarm or other device would be weakest at this point.

In case it is desired to make an entry for an 50 appointment to be kept at a future date, the pull-handle 39 is provided. This handle 39 engages with the front end of the clock by means of the snap springs 40 and 41. When it is desired to make the entry for the future date, the handle 39 is pulled out and is pulled forward until the date 55 desired appears in the opening 11 and the entry is made at its proper place. Meanwhile the paper 14 rolls about the idlers 32, 33, and 34, and feeds from the feed roll 15. After the entry is made, 60 the feed roll 15 is reversed and turned back to the present date by means of the knurled thumb screw 42 and then the pull handle 39 is snapped back into position.

It will be seen from our construction that 65 when the date is changed as mentioned, the paper cannot pull from the power roll 16 since the slots 17 will be engaged with the pins 30.

Adjustments of the power roll can be made 70 by means of the knurled thumb screw 25.

75 The driving pulley cord 20 passes over suitable pulleys 44 positioned at the proper angle to transfer the cord from one plate of the spring pulley to the power roll pulley.

A spring 45 is provided to keep the feed roll 15 80 under proper tension. This spring is pinned to

the opposite chassis walls 46 of the clock and the same spring is pinned at its outer ends to the friction disc 47 which travels against the flange 48 of the feed roll 15.

In the same manner, the spring 49 is fastened 80 to the chassis wall 46 of the clock and at its outer ends to the friction disc 50. These springs are merely strips of suitable spring metal.

In Figure 7, it will be seen that the actual tripping mechanism is on the righthand side of 85 the clock case while there are pins on each side. This is necessary since the slots are arranged on both sides of the paper roll so there will not be a tendency for the paper to twist when being rolled on the rolls, and provides uniformity in 90 rolling.

The conventional base supports for the clock are shown at 51.

It will be seen that in operation, all that is necessary to do in the clock is to wind the alarm 95 mechanism daily and set the arrangement for a specified time, preferably at night. In this way, the device requires no further attention since it will automatically change its register in a brief interval at night and will be ready the next morning for reference as to appointments.

It will also be understood that the same motive means can be applied in the case where it is desired to use electrical clocks, as shown in Figure 8, or other clocks driven by weights and so forth. 100

It will be seen that we have arranged this device in the simplest manner to accomplish the result desired and that the result is an appointment clock and arrangement convenient to make entries upon at any present or future date and 110 which arrangement operates automatically and independent of constant adjustment with the exception in the case of the mechanical clock of the winding of the alarm key, and it will be further seen that these elements have been arranged 115 in the simplest practical manner for economical manufacture.

Some changes may be made in the construction and arrangement of the parts of our invention without departing from the real spirit and purpose of our invention, and it is our intention to cover by our claims any modified forms of structure or use of mechanical equivalents, which may be reasonably included within their scope.

We claim as our invention:

1. An appointment clock comprising a clock casing including a vertical clock face, an extended lower portion substantially at right angles to the vertical face, said extended portion having a cut-out portion, a solid base member positioned slightly beneath said cut-out portion, a memorandum ribbon arranged to be fed over the base member and means for driving the ribbon, and means for unrolling the ribbon for purposes of making notations concerning future events, including a pull-out handle attached to the front end of the extended portion, and an idler pulley attached to the pull-out handle over which the ribbon passes.

2. An appointment clock comprising a driving roll, a feed roll, a memorandum ribbon including 140 slots wound on the rolls, a tripping device including a fulcrumed arm including a cam portion and slot receiving points, a pulley driving said driving

roll, a pin secured to the pulley and arranged to move against the cam portion to depress the said 145 arm, said clock including power means for driving said pulley, a friction disc positioned between said pulley and said driving roll and secured to the driving roll, said driving roll being driven by the frictional engagement of the friction disc only 150

when the slot receiving points are not received within the slots.

3. An appointment clock comprising a clock casing including a vertical clock face, an extended lower portion substantially at right angles to the vertical face, said extended portion having a cut-out portion, a solid base member positioned slightly beneath said cut-out portion, a memorandum ribbon arranged to be fed over the base member, means for driving the ribbon including a driving roll, a feed roll and means for driving the driving roll, said ribbon including equally spaced slots on its edges, a tripping device including a fulcrumed arm including a cam portion and slot receiving points, a pulley driving said driving roll, a pin secured to the pulley and arranged to move against the cam portion to depress the said arm, a friction disc between said pulley and the driving roll and secured to the driving roll, said driving roll being driven by the frictional engagement of the friction disc only when the slot receiving points are not received within the slots.

4. An appointment clock comprising a clock casing including a vertical clock face, an extended lower portion substantially at right angles to the vertical face, said extended portion having a cut-out portion, a solid base member positioned slightly beneath said cut-out portion, a memorandum ribbon arranged to be fed over the base member, means for driving the ribbon including a driving roll, a feed roll and means for driving the driving roll, said ribbon including equally spaced slots on its edges, a tripping device including a fulcrumed arm including a cam portion and slot receiving points, means for operating the tripping device, spacing means for allowing accurate positioning of said slots with respect to the cut-out portion to cause correct positioning of the memorandum therein.

40 5. An appointment clock comprising a clock

casing including a vertical clock face, an extended lower portion substantially at right angles to the vertical face, said extended portion having a cut-out portion, a solid base member positioned slightly beneath said cut-out portion, a memorandum ribbon arranged to be fed over the base member including a driving roll, a feed roll, and means for driving the driving roll, said ribbon including equally spaced slots on its edges and a tripping device including a fulcrumed arm including a cam portion and slot receiving points, means for operating the tripping device, and means for unrolling the ribbon for purposes of making notations of future events including a pull-out handle attached to the front end of the extended portion, and an idler pulley attached to the pull-out handle over which the ribbon passes.

6. An appointment clock comprising a clock casing including a vertical clock face, an extended lower portion substantially at right angles to the vertical face, said extended portion having a cut-out portion, a solid base member positioned slightly beneath said cut-out portion, a memorandum ribbon arranged to be fed over the base member and means for driving the ribbon including equally spaced slots in its edges, a tripping device including a fulcrumed arm including a cam portion and slot receiving points, a pulley driving said driving roll, a pin secured to the pulley and arranged to move against the cam portion to depress the said arm, means for unrolling the ribbon for purposes of making notations concerning future events including a pull-out handle attached to the front end of the extended portion and an idler pulley attached to the pull-out handle over which the ribbon passes.
